UNITED STATES PATENT OFFICE.

WILLIAM P. JORDAN, OF WASHINGTON, DISTRICT OF COLUMBIA.

HOISTING AND TRANSPORTING MECHANISM.

SPECIFICATION forming part of Letters Patent No. 434,278, dated August 12, 1890.

Application filed April 28, 1890. Serial No. 349,716. (No model.)

To all whom it may concern:

Be it known that I, WILLIAM P. JORDAN, a citizen of the United States of America, residing at Washington, in the District of Columbia, have invented certain new and useful Improvements in Hoisting and Transporting Mechanism, of which the following is a specification.

My invention is designed, principally, to take the place of hod-carriers, and to raise material—such as brick and mortar—used in the construction of buildings, and to transport the same to the point where they are required for use, the apparatus being designed for variable heights and for different distances of horizontal movement.

The invention consists, essentially, of a tower composed of sections, and a hoisting-car adapted to receive and raise vehicles which contain material, and a pair of wire-rope cables forming inclined ways, or a series of them extending from the tower to the point or points where the material is to be delivered.

In the accompanying drawings, Figure 1 represents a vertical section of the tower and car with the ways in side elevation. Fig. 2 represents a modification of the tower within a building. Fig. 3 is a side view of the brake. Fig. 4 is a cross-section of the tower, showing the cars and track in plan view. Fig. 5 is an enlarged front view of a bottom section of the tower, showing a side section, partly in section. Fig. 6 shows the relative arrangement of the car and the cable and its supporting-pulley. Fig. 7 is a perspective view of a cap which holds the sections together.

In the drawings, the tower represented in Fig. 1 is composed of sections built of timber, as shown, the sections D consisting of front sections a and side sections b, these sections a and b being held together by bolts c to form one section of the well for the hoisting-platforms A. At suitable intervals on the front sections a are cross-beams, as shown at d, and beams d' to carry the way for the elevator. The side sections b are suitably braced, as most of the strain comes on these sections. I have also shown guys e for bracing each of the sections. The interior of the structure shows a hollow shaft clear throughout from top to bottom, and adapted to allow the free

passage of a hoisting - platform, which is shown at A in Figs. 1 and 2. These platforms are preferably made in series, one above the other, as illustrated in the drawings. The 55 hoisting-platform is provided with a hoisting-rope f, which runs over a pulley g and is carried thence downward, with suitable guiding-pulleys to a hoisting-engine. At the base of the tower I have shown an excavation at B, 60 which is boxed up, so as to be substantially air-tight, and into this the platform fits with approximate accuracy, the fit being such that in case the car should fall the air in the excavation will act as a cushion to break the 65 force of the shock. The platform is provided with tracks, preferably two sets, as shown in Fig. 4. These, when the platforms are down, are in line with tracks h on the ground by the side of the tower, so that the cars loaded with 70 brick or other materials, may be run onto the platforms. The platform being down in the pit, as shown in Fig. 1, the cars are run onto the platform from the tracks h. The cars are made small, so that two of them may be accommodated on one track, and one platform will thus carry four. The cars are provided with small wheels k, adapted to run on the tracks. The upper platform being filled, the platform is raised until the next in order 75 comes in line with the outside track, and this is filled, and so on to the end. Then the platform is hoisted until it comes to the cable-way C, where it is desired to transfer the cars to the point where the material is to be 80 delivered. This cable-way is composed of two cables, the outer end of which is fixed in any suitable manner at the discharge-point and the inner ends are carried over guides or pulleys on the corner or side posts between 85 any two of the beams d, according to the height of the discharge-point or the distance from the tower. The inner ends are then brought down to a drum l, by means of which they may be put under the proper tension 90 and adjusted as to length. The cars are provided with an upper set of wheels m, set upon journals in the side. These wheels are grooved to adapt them to run on the cable C, and the cable is set so as to register with the 95 grooves in these wheels. The inclined platform n is also adjustable and is placed oppo-

site the beam next below the cable C. Here the operator stands and runs the cars off of the platform A onto the cables C. This platform is set at an inclination downward a little more than the inclination of the cables, so as to support the car in its transfer from the platform to the cable. The lower wheels k of the car run upon this platform until the upper wheels get their bearing upon the cables. The cables are set slightly inclined, so that the cars move by gravity from the tower to the point of discharge.

In Fig. 2 I have shown the same form of tower, but arranged to be set inside of a building to lower the empty cars to the ground. From here they are returned to the supply-station, filled, and again taken to the hoisting-tower. The hoist-rope f' here runs over a pulley g', controlled by the automatic brake, which, Fig. 3, consists of a lever pivoted at 4, so as to draw upon a strap 2 and grip the wheel 3, which is fixed to or a part of the hoisting-pulley g'. A weight 5 applies the brake, and a hand-cord C, extending within reach of the attendant, allows the brake to be taken off. To the other end of the rope f' is attached a weight W, which is heavy enough to return the empty platform A to any desired height, as the operator desires, by applying or releasing the brake. When the platform is filled with the empty cars and the brake released, it will return to the ground.

By this mechanism bricks may be hoisted at any point where they may happen to be, hoisting being done by steam-power, and then they are transported by gravity to a point where they are to be used, or mortar or any

other kind of material may be raised and moved in the same manner, the distance practically depending upon the height of the tower, which may be heightened by adding more sections, each section being guyed.

In Fig. 7 I have shown a socket o made of metal, which I use to hold one section from slipping off the top of the next lowest. In practice I prefer sections sixteen feet in length, although the length may be varied.

I claim as my invention—

1. An apparatus for builders' use, comprising a tower composed of sections supported one upon the other and provided with openings and inclined platforms thereat, a hoisting cage or platform movable within the tower, a wheel-carrier on the platform, and adjustable tracks consisting of flexible ropes leading from the openings in the tower, substantially as described.

2. An apparatus for builders' use, comprising a tower composed of sections supported one upon the other and provided with openings, a hoisting cage or platform movable within the tower, a wheeled carrier on the platform, adjustable tracks consisting of flexible ropes leading from the opening in the tower, and the drum on the tower for holding the end of the rope and adjusting the same to alter the length of the track, substantially as described.

In testimony whereof I affix my signature in presence of two witnesses.

WILLIAM P. JORDAN.
